UNITED STATES PATENT OFFICE.

WILLIE D. WHITNEY, OF HOLLEY, NEW YORK.

WASHING-MACHINE.

SPECIFICATION forming part of Letters Patent No. 766,477, dated August 2, 1904.

Application filed December 17, 1903. Serial No. 185,572. (No model.)

To all whom it may concern:

Be it known that I, WILLIE D. WHITNEY, a citizen of the United States, residing at Holley, in the county of Orleans and State of New York, have invented a new and useful Washing-Machine, of which the following is a specification.

This invention relates to certain improvements in washing-machines, and has for its principal object to provide a novel form of machine in which the clothes are subjected to a combined rubbing and squeezing action with a view of removing the dirt in a thorough and expeditious manner.

15 A further object of the invention is to construct a washing-machine in which provision is made for adjusting the parts to accommodate varying quantities of clothes.

20 A further object of the invention is to provide a novel form of washing-machine in which a tub or tank is so mounted that it may be readily oscillated in a horizontal path either by hand or power and at the same time moved vertically to effect alternate compression and release of the clothing under treatment.

25 With these and other objects in view, as will hereinafter more fully appear, the invention consists in the novel construction and arrangement of parts hereinafter described, 30 illustrated in the accompanying drawings, and particularly pointed out in the appended claims, it being understood that various changes in the form, proportions, size, and minor details of the structure may be made 35 without departing from the spirit or sacrificing any of the advantages of the invention.

In the accompanying drawings, Figure 1 is 40 a perspective view of a washing-machine constructed in accordance with the invention, a portion of the tub or clothes-container being broken away in order to more clearly illustrate the construction. Fig. 2 is a transverse sectional elevation of the machine. Fig. 3 is a plan view of the tub proper with the upper rubbing member removed. Fig. 4 is a plan view of the base and cam-track of the machine, the tub being removed. Fig. 5 is a detail sectional view, on an enlarged scale, illustrating a slight modification of the invention. Fig. 50 45 50 55 60 65 70 75 80 85 90 95 100 6 is a similar view illustrating a further modi-

fication. Fig. 7 illustrates a still further modification of the invention. Fig. 8 is a sectional elevation illustrating a still further modification of the invention.

Similar numerals of reference are employed 55 to indicate corresponding parts throughout the several figures of the drawings.

The tub 1 is supported on a base-frame comprising a metallic ring 2, having a central hub member 3, that is connected to the ring 60 by a plurality of radially-disposed arms 4, of which there may be any desired number. Each of the arms 4 is provided with a socket 5 to receive the upper reduced end of a removable supporting-leg 6, so as to permit ready 65 removal and renewal in case of injury. The upper face of the frame 2 is provided with a plurality of cam-faces 7, three being illustrated in the present instance and these being arranged to form alternate projections 70 and depressions, so that when the tub is oscillated in a horizontal plane it will be reciprocated in a vertical line. At the edge of the ring is a socket member 8, preferably cast integral with the ring and serving to receive an 75 arm 9, which may be bolted or otherwise rigidly secured within the socket. The arm 9 is bent upward and terminates in a socket member 10 for the reception of one arm of a yoke 12, that supports the adjustable member 13 of 80 the machine, and said arm may be rigidly locked in position by means of a screw 14 when the position of the member 13 has been adjusted in accordance with the quantity of clothing in the tub.

The bottom of the tub is provided with a pendent spindle or pin 15, fitting through a central opening formed in the hub member 3, and from the bottom of the tub depend hangers 16, having bearings for the reception of 90 the end spindles of grooved rollers 17, that run on the cam-track 7.

On the upper surface of the tub-bottom are arranged any desired number of radially-disposed rubbing-ribs 18, which may be of any 95 ordinary construction, or the ribs may be disposed in any manner common to washing-machines of this general type.

The rubbing member 13 is in the form of a disk of a diameter slightly less than the in-

ternal diameter of the tub and also provided with radiating rubbing-ribs 19, and this disk is further provided with a large number of perforations 20, through which the surplus water may pass when the clothes are squeezed.

In the operation of the device as thus far described the disk 13 is removed and the clothing placed in the bottom of the tub together with a sufficient quantity of water, which may be of any temperature and carrying any suitable detergent in solution. The rubbing member 13 is then placed on top of the clothes and forced more or less tightly down thereon, after which it is locked in position by means of the set-screw. The operator then grasps the edge of the tub, which may be provided with a suitable handle or handles for the purpose and oscillates the same in a horizontal plane. This causes the movable rubbing-ribs of the tub and the stationary ribs of the disk 13 to operate on the clothing and rub the dirt therefrom. During the oscillatory movement the rollers 16, traveling on the cam-tracks, are moved in a vertical plane and carry with them the tub and the clothing against the stationary perforated disk 13. On upward movement of the tub the clothes are squeezed to an extent proportionate to the adjustment of the disk 13, and most of the water is forced from the clothing up through the perforations in the disk. When the tub descends, the water is sucked in through the perforations and again saturates the clothes, and as this movement is kept up with alternate squeezing and releasing of the clothes the dirt loosened by the action of the rubbing-ribs will be gradually taken up by the water and leave the clothes in condition for any further subsequent treatment which may be necessary.

In some cases, especially where large quantities of clothes are to be washed, the strain on the operator may be relieved by employing the construction shown in Fig. 5. The pendent spindle 15 of the tub serves as a guide for a spider 21, carrying a plurality of rollers 16', that run on the cam-track 7'. The bottom of the tub is provided with a circular trackway 23, which rests directly on the rollers, so that when the tub is oscillated the movement will be slower, owing to interposition of the rolling members between the two stationary tracks 7^a and 23.

The construction may be further modified, as shown in Fig. 6, by providing the tracks 23' with slots 24 for the reception of antifriction-balls 25 of comparatively large diameter, the diameter of these being greater than the distance between the highest and lowest points of the cam, and said balls enter a grooved cam-track 7^b, carried by the frame.

In all of the constructions named the clothes receive both a rubbing and a squeezing effect, so that cleansing may be both thoroughly and rapidly accomplished, while the adjustability

of the stationary rubbing member 13 permits the operator to wash any desired quantity of clothes within ordinary limits at one operation.

In order to add to the value of the machine, the vertically-disposed arm 10 is provided with a laterally-extending arm or bracket 26 for the support of a wringer, so that the clothing may be passed directly from one tub to another without the necessity of handling or the removal of the wet clothes. 75

In some cases the structure may be modified by reversing the position of the cam, as shown in Fig. 7. In this case the cam-track 7' is arranged on the bottom of the tub, and the rollers 17' are carried by the base of the machine. In this case the operation is the same as that previously described. 80

It is obvious that the adjustable rubbing member 13 may be supported in a number of different ways. In Fig. 8 I have illustrated a construction in which the central hub member 3 is provided with a vertical bar or standard 30, that extends up through the center of the tub. The central portion of the bottom of the tub is provided with a vertical tube 31, that fits over the bar 30 and is a height about equal to the depth of the tub, so that there will be no danger of leakage of water down the tube. Fitting over the exterior of the rod and tube is a second tube 32, that carries the rubbing member 13', and this second tube has a threaded opening for the reception of a clamping-screw 33, by means of which the adjustable rubbing member 13' may be firmly locked in adjusted position. In this case the arrangement, while somewhat modified, will result in practically the same operation as that already described. 95

Having thus described the invention, what is claimed is—

1. In a washing-machine, a pair of rubbing members, one of which constitutes a clothes-receiver, one of said members being mounted for oscillatory movement with respect to the other, and means for moving one of said members toward and from the other to thereby alternately squeeze and release the clothing during the rubbing operation. 100

2. In a washing-machine, a pair of rubbing members, one of which is perforated, and the other of which constitutes a receiver for the clothing, both of said members being disposed horizontally and in parallel relation, one of said members being mounted for oscillatory movement with respect to the other, and means for moving one of said members toward and from the other to thereby alternately squeeze and release the clothing during the rubbing operation. 115

3. In a washing-machine, a stationary perforated member, a tub having a rubbing-surface, said tub being movable in a horizontal plane and being further movable vertically in the direction of the stationary member to alternately press and release the clothes. 125 130

4. In a washing-machine, an oscillatory tub, cams for effecting vertical movement of the same during its oscillatory movement, and a stationary disk arranged within the tub and provided with perforations.

5. In a washing-machine, a tub mounted for oscillatory movement in a horizontal plane and provided with a rubbing-surface, means for vertically reciprocating the tub during its horizontal movement, and an adjustable disk disposed within the tub and also provided with rubbing-surfaces.

6. In a washing-machine, a tub mounted for oscillatory movement in a horizontal plane, cams on which the tub is mounted and serving to effect vertical play thereof, and a disk disposed within the tub and provided with perforations.

7. In a washing-machine, a tub mounted for oscillatory movement in a horizontal plane, cams forming a support for the tub and adapted to reciprocate the same in a vertical plane, said tub having a rubbing-surface, a disk disposed within the tub and having a rubbing-surface, said disk having also a plurality of perforations, and means for adjustably supporting said disk.

8. In a washing-machine, a tub mounted for oscillatory movement in a horizontal plane, a base or support having a cam-track, tub-supporting rollers disposed on the track, and a stationary disk member disposed within said tub and provided with a rubbing-surface.

9. In combination, a base having a cam-

track, a tub, rollers disposed between the tub and the track, and a stationary member coacting with the tub for operation on the clothes.

10. In combination, a base having a cam-track, a tub mounted for oscillatory movement in a horizontal plane, rollers disposed between the tub and the track, a standard carried by the base, a perforated disk disposed within the tub, a yoke-like bar carrying said disk, and means for adjustably connecting the bar to the standard.

11. In a washing-machine, the combination with a base having leg-receiving sockets, legs extending within said sockets, a cam-track forming a part of the base, a tub mounted for oscillatory movement in a horizontal plane, rollers carried by the tub, and bearing on the cam-track, a standard secured to the base and provided with a socket member, a disk disposed within the tub and provided with perforations, rubbing-surfaces on the disk, and the bottom of the tub, a yoke-like arm secured to the disk and adapted to the socket portion of the standard, and means for locking said arm in adjusted position, substantially as specified.

In testimony that I claim the foregoing as my own I have hereto affixed my signature in the presence of two witnesses.

WILLIE D. WHITNEY.
